Patented Nov. 18, 1919.

UNITED STATES PATENT OFFICE.

ROBERT W. SCHWEIMLER AND PAUL A. POULALION, OF WHEELING, WEST VIRGINIA.

COMPOSITION TILE.

1,322,004.

Specification of Letters Patent. Patented Nov. 18, 1919.

Application filed January 14, 1918. Serial No. 211,829.

To all whom it may concern:

Be it known that we, ROBERT W. SCHWEIMLER and PAUL A. POULALION, citizens of the United States, and residents of Wheeling, 5 in the county of Ohio and State of West Virginia, have invented certain new and useful Improvements in Composition Tiles, of which the following is a specification.

Our invention is an improvement in composition tiles, and consists in certain novel constructions and combinations of parts hereinafter described and claimed.

In the drawings:

Figure 1 is a perspective view of a wall 15 and floor composed of the improved tile;

Fig. 2 is an enlarged end view of a portion of the floor construction;

Fig. 3 is a perspective view of a modified construction; and

Fig. 4 is a sectional view showing the 20 method of forming columns.

In the present embodiment of the invention, the improved tiles are constructed of the fireproof composition forming the subject matter of our Patent No. 1,255,236, granted February 5, 1918, the said composition being not only fireproof, but making a tile not requiring to be baked and in which nails may be driven the same as in wood.

30 In Fig. 1 a portion of a wall is shown, and a section of floor, both constructed of the improved tile. The floor construction is composed of hollow blocks 1, which are substantially rectangular in cross section, having at their bottom edges laterally extending ribs 2, which are adapted to abut as shown in Fig. 1 to space the side walls of the tiles from each other, in order that a filling 3 of concrete may be arranged be-

40 tween the adjacent tiles, and above the same, to form a level surface. Each tile has on its side walls at the outer faces thereof ribs 4 which are substantially triangular in cross section, for gripping into the concrete to 45 prevent vertical displacement of the tiles with respect to each other. Each tile may have upon its upper face a longitudinally extending central rib 5, forming a nailing member for the floor boards 6.

50 These ribs, as shown in Fig. 2, may be formed of the same material as the tile and integral therewith, or, as shown in the floor in Fig. 1, they may be replaced by wooden ribs or bars 7, which are nailed directly to the tiles, the flooring 6 being nailed to the 55 bars.

In Fig. 2 it will be observed that sleepers 8 are arranged upon the ribs 5 and connected thereto by nailing, the floor boards 6 being secured to the sleepers. In Fig. 1 the sleepers 7 are laid directly on the tiles and the floor boards 6 are secured to the sleepers. In the wall construction of Fig. 1, a portion of the wall is formed from the tiles arranged with their chambers or cavities vertical, 65 while another portion is arranged with the chambers or cavities horizontal. In both cases, however, the tiles are similar. Each of the tiles 9 has the oppositely extending ribs or flanges 10 at the opposite sides of one 70 face, and these ribs are adapted to abut the tiles of the adjacent course to properly space the blocks with respect to each other. As shown at the right of Fig. 1, the tiles of one vertical course have the ribs 10 at the inner 75 face of the wall, while the tiles of the series at each side have the ribs 10 at the outer face. Thus the ribs 10 of each tile abut the side walls of the adjacent tile, forming thus a substantially rectangular open space extending from the top to the bottom of the wall. In the wall section at the left of Fig. 1, the tiles 12 have the ribs 13 corresponding to the ribs 10 of the tiles 9, and the tiles in the present instance are arranged in horizontally extending series. Sundry of the registering tiles of the series at the right of Fig. 1 have transversely extending ribs 14 intermediate their ends for the connection of the wood trim 15 of the wall, the said 80 trim being connected directly to the ribs by nails. In the tiles at the left of Fig. 1 these ribs 16 extend longitudinally of the tiles for the same purpose.

85 In Fig. 3 the tiles 17 are similar to those used in the floor construction, having the side ribs 18, a nailing rib 19 for the flooring extending transversely of the tiles on the under face thereof, and this construction is especially adapted for upper floor work. In 90 the wall construction of Fig. 1 the plaster coat 20 is placed directly on the inner face of the wall formed by the tiles. In Fig. 4 is shown a wall construction corresponding to that at the right of Fig. 1, tiles 9 being 95 used, provided with the ribs 10, but at regular intervals vertical courses of tiles 21 of greater thickness are provided. These tiles 21 have the ribs 22 corresponding to the ribs 10, but it will be evident that when the 100 tiles 21 are placed with one face flush with the adjacent faces of the tiles 9 the other 105 tiles 21 are placed with one face flush with the adjacent faces of the tiles 9 the other 110

face will extend inwardly or outwardly, as the case may be, to form the column, and the cavity of the column may be filled with concrete, as shown at 23. Within this concrete is arranged reinforcing bars 24 of steel or the like.

The substantially rectangular openings 25 between the tiles of adjacent courses are adapted to carry pipes of any character, and 10 the tile is adapted not only for wall, floor and partition construction, but is useful for air ducts, heat flues, vent flues, wire and pipe shafts and column forms. As pointed out in our application above mentioned, the tiles 15 are made of a fireproof composition which is mixed in a plastic state and formed in molds. All of the tiles may be reinforced with metal bands, as, for instance, wire, when desired. The absence of interior ob-

structions in the tiles especially fits them for 20 use as ducts and shafts.

We claim:

A floor construction comprising tiles, each tile being formed of nail penetrating material having at its lower face oppositely extending flanges adapted to abut the corresponding flanges of adjacent cores to space said tiles, each tile having its side walls provided with ribs, a facing of plastic material filling the spaces between the tiles above 30 said flanges and interfitted between and retained in position by said ribs, and a nailing rib formed integrally upon each tile and extending transversely across the bottom face thereof and having a length equal to 35 the width of said bottom face.

ROBERT W. SCHWEIMLER.
PAUL A. POULALION.
